UNITED STATES PATENT OFFICE.

WILLIAM J. KELLY, OF READING, PENNSYLVANIA, ASSIGNOR TO CURTIS & JONES CO., OF READING, PENNSYLVANIA, A CORPORATION OF PENNSYLVANIA.

METHOD OF MAKING FOOTWEAR.

1,113,562.

Specification of Letters Patent.

Patented Oct. 13, 1914.

Application filed April 25, 1912. Serial No. 693,202.

To all whom it may concern:

Be it known that I, WILLIAM J. KELLY, a citizen of the United States, residing at Reading, county of Berks, and State of Pennsylvania, have invented a certain new and useful Method of Making Footwear, of which the following is a specification.

This invention is a method of making foot-wear, more particularly boots and 10 shoes, and the object of the invention is to make such boots and shoes in a simple, efficient and economical manner, and to produce a shoe which is particularly sightly and durable.

15 Shoes made in accordance with my method have all the appearances, as well as the wearing qualities, of the well known Good-year welt shoes, and yet may be manufactured at very considerably reduced cost.

20 With the foregoing objects in view, the method, in its entirety, preferably embodies the following operations: applying an adhesive to the bottom, *i. e.*, under-surface, of an insole, when in position on a last, fitting 25 the lining of the upper closely to the last, *i. e.*, lasting said lining, and folding the edges of said lining onto the insole and in contact with the moist adhesive, whereby said lining is made to conform perfectly to 30 the last and is secured to the insole by said adhesive; then applying a seat slip, preferably leather, to the insole at the heel seat, whereupon a counter, preferably molded, is fitted over the heel seat and slip, and thereby 35 made to embrace a portion also of the lining of the upper, said counter being then tacked down into position. The foregoing operations embody the salient features of the new method, but all the operations described 40 need not necessarily be used, or in the precise order enumerated. The operations or steps described are succeeded by others, in order to complete the shoe, such as the following:

45 applying a filling, preferably of a plastic nature containing cork, to the under surface of the insole and overlapping edges of the lining of the upper; then tacking on the outersole and lasting the upper, said upper being attached to the outersole and beneath 50 the edge of the insole, either by stapling or sewing, leaving the outer edge of the upper free; a welt is then positioned upon said free edge of the upper and over the edge portion of the outer sole, whereupon the 55 upper, welt and outersole are sewed to-

gether, this stitching being exteriorly of the prior stapling or sewing of the upper to the outer sole.

In the accompanying drawings, I have illustrated one practical embodiment of the 60 invention, but the construction shown therein is to be understood as illustrative, only, and not as defining the limits of the invention.

Figure 1 is a perspective view illustrating 65 the steps of lasting the lining of an upper and attaching the edge portion of said lining to an insole when in position upon a last, said lining being lasted separately from the upper. Fig. 2 is a perspective 70 view showing the lasted lining of Fig. 1 in connection with the operation of building up the heel portion upon the insole and securing a counter in position over the built up heel portion of the insole and the lining. 75 Fig. 3 is a vertical longitudinal section through the parts of Fig. 2, a portion of the last being shown. Fig. 4 is a vertical longitudinal section showing the step of applying a plastic filling over the folded edge of the 80 lining, the built up portion of the heel and the edge portion of the counter, said plastic filling covering the surface of the insole, and the aforesaid parts to which it is applied. Fig. 5 is a vertical longitudinal section of the parts shown in Fig. 4 with the 85 outersole attached to the upper, said upper being lasted over the lining subsequent to the operation of drawing said lining over the last, a welt being secured to the edge 90 portion of the outersole in a manner to conceal the means for attaching the edge portion of the upper directly to the outersole. Fig. 6 is a cross section on the line 6—6 of 95 Fig. 5, and Fig. 7 is a detail section, on the line 7—7 of Fig. 6, illustrating the row of staples by which the upper is attached to the outersole so as to leave a free edge portion on the upper in position to be covered by the welt.

100 In carrying out the invention an insole A is first applied to a last B. Said insole is so cut that its length and width slightly exceeds the length and width of the last, it being preferred to make the insole somewhat larger than the last upon which said insole is to be positioned, whereby the edge portions of the insole will extend from one-thirty-second ($\frac{1}{32}$) to one sixteenth ($\frac{1}{16}$) of an inch beyond the last. A lining C and an 105

upper D are prepared and attached in the ordinary way, but instead of lasting the upper and its lining simultaneously, as is ordinarily practised in the art, the lining C is lasted independently of upper D. After the insole is properly placed upon the last, with or without tacking said insole to the last, the lining C is drawn tightly around said last so as to conform perfectly thereto. The 5 edge of lining C is folded over the protruding edge of insole A, as indicated at c, whereby the edge of the lining is adapted to be secured in position by suitable means, preferably an adhesive or cement. Prior to, 10 or during the operation of, lasting the lining, a layer of adhesive material, such as cement, is applied to the bottom or under surface of insole A. Now when the lining is drawn around the last and the edges c 15 of said lining folded over the protruding edge of the insole and upon the adhesive upon the bottom face thereof, said edges c of the lining are pressed firmly down upon the adhesive, whereby the folded edges of 20 the lining are attached securely to the insole. The next step is to apply a counter to the insole and to the lining after the latter shall have been drawn over the last. For the purpose of snugly fitting the counter 25 over the heel seat of the insole, it is preferred to apply a heel seat slip E to the heel seat of said insole, and thereafter the counter F is placed in position over the lining and the seat slip. Said seat slip E 30 is composed, preferably, of leather cut to the desired shape, and it is placed in position over the infolded edges c of the upper lining C at the heel portion of the insole. It is not essential to use the heel seat slip E, and 35 when a good heavy insole is used, in the manufacture of the shoe, this slip E may be entirely omitted. Counter F is, preferably, molded according to the size and shape of the shoe, said counter being provided with 40 an inwardly extending flange f. The counter may be composed of leather, or any other suitable material, and it is molded to conform to the shape of the heel, said counter being a comparatively stiff member. When 45 the counter is placed in position it incases the heel portion of the lining, and its flange f extends across and incases the edge portions of the seat slip, said counter being secured in position by suitable means, such 50 as the lasting tacks f' which are shown in Fig. 3 as passing through the counter and into the seat slip, but, obviously, these lasting tacks may be long enough to extend through the folded edges c of the lining and 55 into the insole, or even into the last. The procedure just described constitutes an improvement in the art of making shoes and possesses many advantages, among which are the following: The lining C of 60 the upper is made to conform perfectly

to the last, and it is attached securely to the insole; it is preferred to build up the heel portion of the shoe so as to securely attach the counter to the heel seat of the insole; the counter is easily, quickly and accurately 70 placed in position so that it fits snugly to the lining and incases the edge portion of the seat slip, and the operations are easily and quickly performed.

After proceeding as heretofore described, 75 the shoe is finished by lasting the upper and by securing an outersole to said upper. The preferred mode of procedure in finishing the shoe is shown in Figs. 4 to 7, both inclusive, to which reference will now be made. 80 A filling G is applied to the under face of the insole in a manner to cover said insole, the folded edges c of lining C, the inturned flange f of the counter, and the seat slip. This filling may be composed of any suitable material, although it is preferred to employ a self-hardening composition containing cork. The filling is applied to the insole and the correlated parts to produce a layer substantially uniform in depth, the top 85 surface of the filling conforming substantially to the contour of the outersole. After the heel lift H and the outersole I shall have been placed in position, they are tacked to the last in the ordinary way, for the purpose 90 of retaining them in proper relation during the lasting of the upper. Said upper is drawn tightly over the last and the stretched or taut lining C, the edge portion of the upper overlapping the edge portion of the 95 outersole. According to one mode of procedure the upper is fastened to the outersole substantially beneath the edge of the insole, and this attachment of the upper to the 100 outersole is independent of the attachment 105 of the edge c of the lining to the insole. In Figs. 5, 6 and 7 of the drawings the edge portion d of the upper laps the edge portion of the outersole, and said lapped portion of the upper is fastened to the outersole by 110 stapling or stitching the parts together. Fig. 7 illustrates a row of staples J for attaching the upper to the outersole within the free edge d of said upper, and during the lasting 115 operation the edge of the upper is drawn around the edge of the insole so that the staples J may be positioned substantially within said edge of the insole, whereby the upper is made to conform to the stretched or taut lining and the parts are united in a 120 substantial way. The staples J may be of any suitable form, and they are positioned to pass through the upper and to be embedded within the material of the outersole. After lasting the upper and fastening said 125 upper to the outersole independently of the lining to the insole, a welt is positioned upon the free edge portion d of the upper, the function of said welt being to conceal the staples and to, also, conceal the free edge 130

portion of the upper. The welt K is of any suitable or preferred form and it is positioned over or upon the outwardly extending free edge d of the upper, whereby the 5 welt, the edge d of the upper and the outersole are assembled in lapping relation, as shown in Figs. 5 and 6. The welt and the upper are attached to the outersole independently of the row of staples or the 10 stitches by which the upper is attached directly to the outersole. In this connection it is preferred to sew the welt and the upper to the outersole by a row of stitches indicated at k, the stitches k being independent 15 of the staples J, and the seam formed by the stitches k passing through the welt, the off-standing edge portion d of the upper, and the edge portion of the outersole.

From the foregoing description taken in 20 connection with the drawings it is apparent that the lining C and upper D are lasted independently of each other, and, furthermore, the lining C is attached to the insole independently of the attachment of the upper to the 25 outersole.

An important feature of my invention consists in the use of an insole the dimensions of which slightly exceed those of the last, and in positioning said insole upon the 30 last in a manner for the edges of said insole to protrude beyond the edges of said last. This enables the upper to be lasted under the protruding edge of the insole, whereby 35 staples or staples J are adapted to be positioned under said protruding edge of the insole, see Figs. 5 and 6. The staples or staples J are thus protected in part by the edge of the insole, and they are concealed and protected by the welt K. By having 40 the edge of the insole protrude beyond the staples or staples J, a shoulder is produced after the welt is attached to the outersole, and this precludes the shoe from pulling up, besides imparting to the shoe the exact 45 appearance of a Goodyear welt. A most important advantage following from this organization of the parts is that the entire strain is taken off the upper under the pressure of the foot upon the insole, for the reason 50 that the protruding edge of the upper is attached by staples or sewing to the outer sole on a line inside the edge portion of the insole, see Fig. 6, and upon the outwardly turned edge d of this upper is positioned the 55 welt, the latter being attached to said edge d and to the outer sole by sewing the parts together, as a result of which the upper is relieved from excess strain. Again, by arranging 60 the edge of the insole to overlap the edge of the upper and the welt, water cannot reach the inside of the shoe without soaking through the upper, thus resulting in the production of a substantially waterproof shoe. It is to be observed, further, 65 that the upper is attached to the outersole

by two rows of fastenings, both of which are separate or independent of the attachment of the lining to the protruding edge of the insole; furthermore, one row of fastenings (staples or stitches J) are positioned under 70 and within the protruding edge of said insole, and, again, the welt and the upper are attached to the outersole by a row of stitches k which are separate from the row of staples or stitches J, whereby a strong and durable 75 shoe results from making the shoe according to the procedure of this invention.

Having thus fully described the invention, what I claim as new and desire to secure by Letters Patent is:

1. The method of making shoes which consists in lasting a lining separately from the upper and attaching said lining to an insole, positioning a heel seat slip against the lining, positioning a counter over the 85 lining and heel seat slip, thereafter lasting the upper, then fastening the upper directly to an outer sole on a line substantially within the edge of the insole, and thereafter sewing a welt to the upper and the outer sole by 90 a seam positioned exteriorly to the aforesaid attachment of the upper to the outer sole.

2. The method of making shoes which consists in lasting a lining separately from the upper and uniting said lining to an insole, placing a heel seat slip against the lining, positioning a counter into lapping relation to said heel seat slip and the lining, then lasting the upper over said lining and 100 the counter, then uniting the upper to the outersole independently of the lining and beneath the edge portion of the insole, and then sewing a welt and the upper to the outer sole independently of the aforesaid attachment of the upper beneath the edge of the insole.

3. The method of making shoes which consists in lasting a lining separately from the upper, securing said lining to the insole by 110 an adhesive, placing a heel seat slip against the lining, positioning a counter into lapping relation to said heel seat slip and the lining, then lasting the upper over said lining and the counter, then uniting an outwardly turned edge portion of the upper to an outersole on a line beneath the edge portion of the insole, and then sewing a welt and the outwardly turned edge portion of the upper to the outersole on a line exteriorly to the aforesaid attachment of the 115 welt to said outersole beneath the edge of the insole.

4. The method of making shoes which consists in first lasting the lining of the 125 shoe, placing a heel seat slip against the lining and the insole, positioning a counter over the lining and into lapping relation to the heel seat slip, then lasting the upper, then securing the outersole to the upper, 130

leaving a free edge on the latter, applying a welt upon said free edge, and uniting the welt, upper and outersole together, by a seam independent of the aforesaid attachment of the outer sole to the upper.

5. The method of making shoes which consists in lasting the lining of the upper and securing the edge of said lining to the insole, placing a heel seat slip against the 10 lining and insole, positioning a counter over the lining and into lapping relation to the heel seat slip, then lasting the upper, then securing an outersole to the upper independently of the attachment of the lining to the 15 insole, and thereafter sewing a welt and the upper to the outersole on a line exteriorly of the aforesaid attachment of the upper to said outer sole.

6. The method of making shoes which 20 consists in lasting the lining of the upper and securing the edge of said lining to the insole, then applying a heel lift to the insole, then applying a counter so that its edges fold over said heel lift, then tacking said 25 edges in place, and then lasting the upper and securing it to an outer sole.

7. The method of making shoes which 30 consists in applying an insole to a last, lasting an upper lining and securing its edges to the edges of said insole, then positioning a heel lift on top of said lining and insole, then securing a counter in place with its edge infolded on said heel lift, then lasting an upper over the said upper lining and securing 35 it to the outersole of the shoe separately from said lining.

8. The method of making shoes which 40 consists in applying an insole to a last, lasting an upper lining and securing its edges to the edges of said insole, then positioning a heel lift on top of said lining and insole, then securing a counter in place with its edges infolded on said heel lift, lasting an upper over the said upper lining, securing it 45 to the outersole of the shoe separately from said lining, applying a welt near the outer and upper edge of the outersole and then fastening said upper welt and outersole together.

50. 9. The method of making shoes which consists in applying an insole to a last, lasting an upper lining and securing its edges to the edges of said insole, then positioning a heel lift on top of said lining and insole, then securing a counter in place with its edge infolded on said heel lift, then applying a suitable filling to the insole and over the lasted edges of the lining, and then finishing the shoe by applying a welt near the 55 outer and upper edge of the outersole and then fastening said upper, welt and outersole together.

60. 10. The method of making shoes which 65 consists in fastening a lining to an insole, positioning a heel lift on said insole, secur-

ing a counter in place with its edges overlapping said heel lift, and then positioning an upper and outersole in place and securing them together.

11. The method of making shoes which 70 consists in fastening a lining to an insole, positioning a heel lift on said insole, securing a counter in place with its edges overlapping said heel lift, then positioning an upper and outersole in place and securing 75 them together, then concealing the line of union of the outersole and upper by a welt, and then securing said welt, upper and outersole together.

12. The method of making shoes which 80 consists in conforming an upper lining to a last and securing its edges to an insole, then building up the heel upon the insole, securing a counter in position relative to the insole and the heel, then positioning an 85 upper and outersole in place and securing them together separately from the insole.

13. The method of making shoes which 90 consists in lasting an upper lining, then applying a heel seat slip to the insole, then securing a counter in position relative to the heel seat slip and said lining, and then lasting the upper.

14. The method of making shoes which 95 consists in lasting a lining and securing its edges to an insole, building up the heel portion by applying a heel seat slip to the insole, securing a counter in position to incase the heel seat slip and a part of the insole, and then lasting the upper.

15. The method of making shoes which 100 consists in applying an insole to a last with the edges of said insole protruding beyond the corresponding edges of the last, lasting the upper lining around the last and the protruding edge of the insole, then uniting said lining to the insole, placing a heel seat slip against the insole, positioning a counter over the lining and into lapping relation to the heel seat slip, thereafter lasting the 105 upper, and then uniting an outersole to the upper by fastenings positioned under and within the protruding edge of the insole.

16. The method of making shoes which 110 consists in applying an insole to a last with the edges of said insole protruding beyond the corresponding edges of the last, lasting the upper lining around the last and the protruding edge of the insole, placing a heel seat slip against the insole, positioning a counter over the lining and into lapping relation to the heel seat slip, then lasting said lining to the insole, thereafter lasting the upper over the counter and the heel seat slip and beneath the protruding edge of said 115 insole, applying an outersole, then attaching said outersole to the upper on a line under and within said protruding edge of the insole, and then attaching a welt and the out-turned edge of the upper to the 120 125 130

outersole by sewing the parts together independently of the aforesaid attachment of the upper within the edge of the insole.

17. The method of making shoes which
5 consists in applying an insole to a last with
the edges of said insole protruding beyond
the corresponding edges of the last, lasting
the upper lining around the last and the
protruding edge of the insole, then securing
10 an outersole to the upper independently of
the attachment of the lining to the insole
and by a row of fasteners positioned under

and within said protruding edge of the insole, and finally securing a welt and an edge
15 of the upper to the outersole by an independent row of stitches, said welt being positioned to conceal the first row of fasteners.

In testimony whereof I have signed my name to this specification in the presence of two subscribing witnesses.

WILLIAM J. KELLY.
